UNITED STATES PATENT OFFICE.

WILLIAM GLENN, OF MOUNT VERNON, IOWA.

VOTING-MACHINE.

SPECIFICATION forming part of Letters Patent No. 787,373, dated April 18, 1905.

Application filed May 10, 1902. Serial No. 106,668.

To all whom it may concern:

Be it known that I, WILLIAM GLENN, a citizen of the United States, residing at Mount Vernon, in the county of Linn and State of Iowa, have invented certain new and useful Improvements in Voting-Machines, of which the following is a specification.

The object of this invention is to provide means whereby any voter may exercise the complete right of suffrage, including all the variations and combinations involved therein, limited only by the provisions of law.

The invention consists generally in a machine so constructed as to secure the results above specified, to lock itself against any manipulation which would produce an unlawful result, and to mechanically and successively register the votes as cast, as hereinafter claimed.

The full nature of the invention will appear from the description and claims following, reference being had to the accompanying drawings, forming a part of this specification.

In the drawings, Figure 1 is a side view of a machine embodying my invention, the legs and the extremities of the main operating-levers being broken away. Fig. 2 is an end view as seen from the right of Fig. 1. Fig. 3 is a detail showing parts of the entrance-lever and its connections. Fig. 4 is a similar view of the exit-lever. Fig. 5 is a top view of the machine as in use. Fig. 6 is a detail showing mechanism for unlocking the machine and permitting the voter to vote a straight ticket. Fig. 7 is an end view of the guide for the ticket-selecting sleeve. Fig. 8 is an end view of the mechanism shown in Fig. 6. Fig. 9 is a fragmentary bottom view of the machine with the tabular portion removed, showing the paper-roll for independent voting, the classifying device, and portions of the locking-bars. Fig. 10 is a fragmentary view in perspective showing the general arrangement of the voting-slides, locking bars, and a pawl to engage the counter and related mechanism. Fig. 11 is a detail side view showing one set of voting and locking mechanisms. Fig. 12 is a bottom view of a voting-slide. Fig. 13 is a key by which the slide is moved. Fig. 14 is a side view in detail of the classifying de-

vice and the independent-voting mechanism. Fig. 15 is a view of the classifier in perspective. Fig. 16 is a section showing means for engaging any one of the classifying-bails with an actuating rock-shaft. Fig. 17 is a detail view showing mechanism for grouping any desired number of lock-bars. Figs. 18, 19, and 20 are respectively side, top, and sectional views of a counter for each candidate.

This machine is designed to perform mechanically all the functions possible in a voting-machine. These functions may be defined as follows: The voting and registering of straight party-tickets or split tickets, the vote of each person entitled to a vote being accurately registered and none others; suitable provision for the casting of ballots independently of the regular tickets; mechanical grouping of certain candidates—for example, judges or electors—and provision for the casting of a vote for any one or more individuals of such group, the machine being locked against duplication; the mechanical classification of voters corresponding to their particular rights of franchise at any election, so that any voter may only vote for candidates or questions to which he is entitled by law.

Referring now to the drawings, A is a rectangular frame, which is shown set horizontally on suitable supporting-legs A'. In the case of machines for the larger political divisions (the State of New York, for example) it would be preferable to set the frame perpendicularly, so that the whole voting-table is within easy reach of the operator. At the sides of the frame are standards or supports A'', which carry the deck to which are attached the various tickets, the voting-slides, &c., to be hereinafter described. The ends are closed by end pieces A''' and A''', at what for convenience may be called the "head" and "feet" of the machine, respectively. The side standards also furnish bearings for various rock-shafts, bearings, levers, and cross-rods used in the machine.

Across the top of the machine at intervals wide enough to permit the necessary movement of the voting-slides are attached plates B, provided with flanges B' to take ticket cards or slips B'' and covering strips of glass 100

B³. Only three of these are shown, though of course the number should in practice be sufficient to include all the party-tickets authorized by the law in any case. On cross-bars C below these plates are mounted slides C', each having a keyhole C² in a down-set middle portion C³. Between these slides are stationary cross-strips C⁴, which serve both as guides for the slides and wards for the slide-key C⁵. The blade of the key is preferably corrugated or warded, so as to effectually prevent the substitution of a spurious key, and has a narrow neck at C⁶ to pass between the lateral lugs C⁷ of the slide-guides. 10 Each slide is provided with a depending limb C⁸, and to this is pivoted a pawl D, controlled by a spring D'. This pawl has a wing D² lying directly below the keyhole, so that when the key is thrust down as far as it may 15 go the pawl is lifted out of engagement with the counter-wheels E, which will be more particularly described hereinafter. For convenience the slides are numbered by adjacent numerals, as shown in the top views of the 20 machine.

On a lower set of cross-bars F is mounted a series of slide-rods F', running parallel with the voting-slides, but in different vertical planes, so that the slide-keys pass between 25 said rods. The rods are provided with lateral wings F², beveled on the upper faces for the easy admission of the key. It is evident that when any rod is free to move back and forth it may be moved by an adjacent key inserted 30 from above. At the head end of the machine the rods are looped at F³ to take the cross-rod G of one or more bails G'. By this means any number of the slide-rods may be coupled, so that moving one moves all of the 35 group. This is used where there is a plurality of candidates for one office (electors, for example) and it becomes possible by means of it for a voter to vote for any one or more presidential electors on any one or more 40 tickets, regular or independent, but impossible for him to duplicate, inasmuch as the splitting of the previously-arranged straight ticket or "scratching," as it is commonly called, must be done alternatively, the vote for one 45 candidate being recalled before it is possible to vote for another, as will be more fully explained hereinafter.

The grouping mechanism is clearly shown in Fig. 17 and comprises a rock-shaft G², a 50 series of adjustable arms G', mounted loosely thereon, and rods G of suitable length to include as many slide-rods as may be wanted in any group. In Fig. 17 five are included in one group and two in another, while one 55 of the slide-rods is independent of both. Each machine is supposed to be provided with enough rods G of various lengths to meet the requirements of any election, and before the election the judges would arrange 60 the groups in the machine according to the

groups on the tickets. A supplemental bail G³, long enough to include all the slide-rods and mounted on a rock-shaft G⁴, serves to restore all the rods to the initial position. (Shown in Fig. 11.) The rock-shaft has a lever G⁵, connecting by intermediate links and levers with the exit-lever, so that the raising of the exit-lever brings all the slide-rods to the initial position. 70

On a rock-shaft H is mounted a wing-plate H', with an upturned flange H² to serve as a carrier for all the pawls D in any one row across the machine when the wing-plate is turned to a horizontal position. The nose of each pawl is extended at D³, and this rides on the flange H² when the pawl and voting-slide are pushed to the right. This admits of the voting-slides being moved back and forth at will in arranging the ballot without affecting the counters, as the wing-plate supports the 80 pawls above the succeeding counter-teeth. The wing-plate also serves as a stop to the movement of the pawls and voting-slides unless they are operated in the proper way and with a key of the right shape and length. 90 Each of these wing-plates connects by a lever H³ and connecting-rods H⁴ and H⁵ with the exit-lever, so that in the final movement of the latter the wing-plate falls and allows the pawls to engage the counters at their next 95 succeeding teeth.

Referring to Fig. 11, it is to be understood that the parts are represented in the initial position, with the lock-bars F' moved over to the extreme right (the locking position) and out of register with the slide C' and its key C⁵, which in action passes between the wings F² F² and is thrust down far enough to reach the wing D² of the pawl D and lift the pawl out of engagement with the counter E. In 100 the position shown the voter can do nothing until one or more of the voting-slides is moved to the right in register with the lock-bars—that is to say, until the keyhole C² is directly above the space between the wings F². This is done as to a whole ticket of such 105 slides by the action of the entrance-lever, as explained elsewhere. Once in register he may now move back a single slide by use of the key and may then move up to voting position a slide for this same or any other candidate for the same office. 110

On cross-bars F' are mounted slide-rods F⁵ directly below the slide-rods of the upper series. They are provided with lateral wings 115 or lugs F⁶, adapted to engage the depending limbs of the voting-slides and move them in one direction—that is to say, back to the primary position. Near the foot of the machine these secondary slide-rods connect with as 120 many sectors I, mounted loosely on a long sleeve I' on a rock-shaft I², extending across the machine. On the sleeve is also mounted a series of bails I³, having grooved hubs I⁴, adapted to engage with studs I⁵ in the rock- 125

shaft projecting through slots I^6 in the sleeve. The bails are set at different radial angles, as shown, and are adapted to engage studs or screws I^7 , projecting from the rims of the sectors. Any bail may move independently of any other, and by inserting screws or studs in the sector in the path of its movement it moves such sectors without affecting the position of any others. By this means it is possible to classify voters according to their qualifications—as, for example, women, who may exercise a limited suffrage, citizens living outside a precinct, but who may vote therein as to township officers, &c. One of the bails I^8 is made fast to the sleeve, which has a limited rotary movement on the rock-shaft. To the shaft is attached a crank I^9 , adapted to engage with a hook J , connecting by intermediate mechanism, hereinafter to be described, with the entrance-lever. By sliding the rock-shaft endwise it is made to engage by its studs I^5 with any desired bail. The proper position of the rock-shaft with respect to any bail is indicated by a dial or indicator I^{10} , engaging by rack and pinion with the rock-shaft, as shown. To the end of the sleeve adjacent to the crank is secured a sector-gear I^{11} , meshing with a companion gear I^{12} on a short rock-shaft K , to which is also secured a double-armed lever K' and K'' , actuated by the exit-lever through the medium of a hook K^3 engaging a stud K^4 . The operation of this part of the machine is as follows: In the case of a voter entitled to vote only for certain candidates a screw is removed or withdrawn from the path of a bail corresponding to the voting-slide of each of such candidates. The raising of the entrance-lever moves all the slides of some selected ticket to voting position. The lowering of the same lever draws back the hook J , which catching the crank I^9 draws it back and carries with it the bail from the path of which such screws were removed. This movement carries back to the initial position all the voting-slides and connected sectors except those from which the intercepting screws were withdrawn. These represent the lawful ticket of this particular class of voters and the only ticket possible for him to vote; as all other parts of the machine are locked against any attempt he may make to vote illegally. It will be understood that the arrangement of the machine for different classes may be done before the day of election by the proper judges, who also in the case of any voter in a special class will set the machine to correspond to his case before he raises the entrance-lever. The final movement of the exit-lever serves, through the mechanism above described, to move back the bail fixed to the sleeve, and this restores to the initial position all the sectors that have been moved by the voter by contact with the arms I^{13} .

65 The mechanism for the independent ticket

is best illustrated in Fig. 14. L is a roll of paper, the web of which passes over rolls L' and L'' and between feed-rolls L^3 . These are actuated by gearing L^4 , ratchet L^5 , and a double-arm lever L^6 , provided with a pawl L^7 . One such lever connects by a rod L^8 with a cross-bar L^9 , which is moved in one direction by the voting-slides C^{12} and in the other by a rod L^{10} , connecting the other arm with the lever, which operates the classifier and which is finally actuated by the exit-lever. The paper-web passes over a plate L^{11} , which serves as a writing-tablet, and under the slides C^{12} , so that it is impossible to write on the paper until a slide is pushed back, exposing enough surface for a name. In practice these slides have a longer movement than those in the body of the machine and are provided with a depending lip C^{13} to engage the cross-bar L^9 ; otherwise they do not differ materially from those already described. Their coacting slide-rods F^7 slide at one end on a cross-bar F^8 and at the other end each connects with a lever F^9 , to which also lower down one of each of the upper bank of long slide-rods connects. The pawl of the slide D^4 engages a shoulder on a cross-plate D^5 when the slides are in normal position. It is provided with a wing D^6 , adapted to engage a cross-bar D^7 shortly after it is moved to the right, it being understood that at this time the wing-plate H^6 is depressed. This serves to lock the slide almost as soon as it is moved, so that it is impossible for a voter to duplicate or recall his action. Whether he decides to write a ballot or not he must fully operate the slide before he can release the key. It is also to be understood that in uncovering a space for the writing of an independent ballot he has locked the machine as to all other corresponding candidates—that is to say, all the candidates on the same longitudinal line of the machine in the case of single-candidate offices and as to all candidates in all groups. The movement of all the slides is limited by cross-rods F^{10} . In this case, as in all others, the voter must first have moved into voting position some regular party-ticket, and before he can vote independently he must “scratch”—that is to say, move back the voting-slide of—a candidate to whom he objects.

At one corner of the machine corresponding to the head is pivoted the entrance-lever M . M' is a simple dash-pot to absorb the concussion in case the lever is allowed carelessly to fall. This lever connects by a slotted link M^2 with a bell-crank lever N , which is linked to another similar lever N' , secured to one of the pawl-carrying wing-plates and coupled to all the others. It is also linked to a lever G^6 , engaging the grouping mechanism and already described. The entrance-lever also connects by a link M^5 with a shifter M^3 , connecting by a suitable fork with a sleeve O , mounted in bearings O' . Another

shifter M^4 engages the sleeve near the other end and connects with the hook which actuates the classifier already described. The sleeve is positively turned by a shaft O^2 , on 5 which it is free to slide. At one end of the shaft is a pinion O^3 , engaging a sector-gear O^4 , provided with a lever O^5 , which serves as an indicator in connection with an arched plate O^6 at the end of the machine, numbered 10 to correspond with the designating-numerals of the several party-tickets, as shown in Fig. 5. At different points on the periphery of the sleeve and suitably spaced are studs O^7 , one for each party-ticket. A stud O^8 registers 15 when in proper position with grooves in the bearings O^{10} . It is thus impossible to raise the entrance-lever until the indicator registers with a number corresponding to some one of the party-tickets. When so set, the 20 lever may be raised, and in so doing the sleeve slides endwise and engages a lever P , forming a part of a bail P' , extending across the machine behind all the voting-slides of one party-ticket, one of these being provided for each 25 ticket. The bail is moved back when the entrance-lever descends by a collar O^8 , which engages the lever on the opposite side. Thus the first act of the voter on entering is to vote a straight party-ticket. If he now wishes to 30 scratch his ticket, he may do so in the manner already described. It is to be noted that the slotted link M^2 allows the entrance-lever to descend without disturbing the pawl-carriers, which are dropped by the exit-lever, as already described.

At the foot of the machine on the same side as the entrance-lever is the exit-lever Q , which may also be provided with a cushioning dash-pot Q' . To this lever is connected the hook 40 K^3 , which through mechanism already described draws all the voted slides back to the initial position. This is done as the lever descends behind the voter as he goes out. In raising the lever to get out a slotted link 45 draws back the arms connected with the pawl-carriers and the pawls descend to a position to engage a succeeding tooth of a counter, which is of course moved one space as the pawl is drawn back by the final movement of the exit-lever. The lever K^2 connects by a 50 slotted link K^5 with a segmental bevel-gear R , meshing with a pinion R' on the shaft O^2 . This in the final movement of the exit-lever serves to restore the shaft and sleeve to the 55 initial position with the indicator at zero, when the machine is locked. The hook K^3 is liberated from the stud K^4 by the exit-lever itself, which has a stud or shoulder at Q^2 to engage the under side of the hook and lift it from 60 the stud.

It is important that both the entrance and the exit levers be raised the full distance of their travel; otherwise the voter might by stooping awkwardly under a partially-raised lever, as some might be expected to do, get

inside and find the machine locked against him. To prevent this, a lock is provided for each lever, so arranged that unless the lever is completely raised it will not fall again to the original position. This lock is shown in 70 Figs. 3 and 4. S is a double-toothed and double-acting pawl, held in alternative positions by an angular spring S' engaging a pin S^2 . The pawls are pivoted a short distance from the pivot of either lever and are coupled 75 to the slide-shifting mechanism by links S^3 and S^4 . Their teeth engage notches Q^3 in the levers, and they are so coupled that when one is in locking position the other is in the opposite position. Thus in Fig. 4 the lever is 80 locked, while in Fig. 3 it is unlocked, except by other mechanism. Projecting from each lever is a stud Q^4 , (the one on the entrance-lever is concealed by the upper link,) which at a certain point in the movement of either 85 lever, a point near the limit of its travel, strikes a pin S^6 and trips the pawl, reversing its position.

The operation of the device will now be understood. The parts in both figures referred to are in the initial position. If now a voter raises the entrance-lever part way, the pawl engages the lower notch and cannot then be lowered; but if it is raised to the full height the stud Q^4 (see Fig. 4) strikes the pin S^6 and 90 reverses the pawl, when the lever may be lowered. The raising of the entrance-lever has, however, through the system of links and levers referred to, reversed the pawl at the exit-lever, and it is then in position to act 95 in the manner just described. The final movement of the exit-lever returns the parts to the initial position.

An improved counter is shown in Figs. 18, 19, and 20. It comprises a number of ratchets of varying diameters, the units-wheel being larger than the tens-wheel by the depth of all its notches but one and the tens-wheel being correspondingly larger than the hundreds-wheel. One notch in the units-wheel E and one in the tens-wheel E' extends as deep as the notches in the hundreds-wheel E'' . When the slide-pawl reaches this notch in the units-wheel, it catches a tooth of the tens-wheel, and the same is true of the deep notch in the tens-wheel. The wheels are mounted on a fixed shaft provided with a spring-pressed pin T^3 for each wheel, and notches T^4 are formed in the bore of the wheel to engage with the pins. One of these counters is 100 provided for each voting-slide, excepting, of course, the slides of the independent ticket, which need none.

Both the entrance and the exit levers are provided with springs to return them to normal position, so that no carelessness on the part of the operator will prevent their proper action.

In Fig. 5 the outer lines of the voting-booth are indicated by the extended lines at the up- 130

per right and lower left hand corners, it being understood that the booth incloses all the machine except the exit-lever and the indicator of the classifier, which are in plain sight of the judges of election. It is to be understood also that the entrance-lever bars the voter's passage to a position behind the machine and the exit-lever bars his progress out as he leaves the booth, so that in voting he must operate both levers.

The sequence of operations is as follows: The machine is first made ready before the election by the proper election officers, the proper tickets being inserted, the grouper arranged for multicandidate offices as they occur, and the classifier adjusted to such classes as will appear at the election. The voter first enters the booth and finds his progress barred by a locked lever. If not previously instructed in the use of the machine, he finds a card of instructions at his right. In accordance with that he adjusts the indicator to a number corresponding to the ticket of his choice or that nearest his choice. He then raises the entrance-lever, which drops behind him if he carelessly lets go of it. He has now, as previously explained, moved up to voting position the "voting-slides" or "vote-indicators," as they may be alternatively designated, of one entire party-ticket. In so doing their pawls move a little in advance of the upward movement of the pawl-carriers, so that when they reach their final position to the right, which may be called the "voting" position, they all ride on one of said carriers. The other carriers in the machine, as previously explained, bar the movement of other slides, except as operated by the proper key. If now the voter wished only to vote a straight ticket, he has nothing to do but pass out of the booth at the proper exit, the entrance-lever being locked behind him. Just outside the booth he is barred by the exit-lever, which he must lift. This action drops all the pawl-carriers, when such of the pawls as are in voting position catch a succeeding tooth each of a counter, which registers as the exit-lever descends to normal position. If the voter wishes to scratch his ticket, he may only do so by canceling the initial vote for an objectionable candidate. This he does by moving back the representative slide, which discloses some distinguishing color or symbol in moving to voting position, and with it its appropriate lock-bar. This brings all the unvoted slides in register with the lock-bar, so that the key will operate any one of them, and he may vote the one of his choice, but only one until another is canceled. When his ticket is arranged to his satisfaction, he passes out of the booth, as already described, and his vote is registered. An exception is to be noted in the case of groups, as in this case the cancellation of a vote releases all the other slides in the machine included in the group; but the moving up of

any slide locks all except such as have been moved up, so it is impossible for the voter to duplicate. If the voter wishes to vote for one or more independent candidates, he cancels as above described and may then move a corresponding slide to uncover paper on which to write the name of his candidate. Unlike the rest of the machine, however, he is not in this case at liberty to recall his action except by the cancellation of the name he has deliberately written, as the machine is now locked as to this office, (except in the case of groups, as noted above.) To allow the voter to write, readjust, and move up more paper would of course be impracticable and lead to gross fraud. He may of course vote for other candidates for other offices, (in the case of groups for the same office;) but the construction of the machine is such as to bar him against duplication and fraud.

To some positive and finally-moving part of the machine—the sleeve of the classifier, for example—is attached an arm V, engaging by a connecting-rod V' with a counter to tally the number of votes, such counter not being shown. The register as to individual candidates is counted at the bottom of a horizontal or back of a vertical machine.

In the construction of this machine it has been found most convenient to make the vote designating or indicating member in the form of a slide, though in some machines the part performing a corresponding function is in the nature of a swinging lever, a push-button, or otherwise. The term "vote - designating member" would apply to these and other forms of device for the purpose, as its function is to denote on the general face or keyboard of the machine the particular candidate or question for whom or which the voter arranges his ballot.

As used herein and in the claims the term "out of register" refers to a mechanical juxtaposition or alignment of parts and not to the act of registering or recording the vote.

Having thus described my invention, what I claim as new, and desire to secure by Letters Patent, is—

1. In a voting-machine, the combination of a vote-designating member, a coördinate member normally out of register therewith, and a key adapted to coact with and move both when in register.

2. In a voting-machine, the combination of a vote-designating member, a coördinate member normally out of register therewith, a key adapted to coact with and move both members when in register, and means for moving the coördinate member to normal position, independent of the key.

3. In a voting-machine, the combination of a voting-slide, a coördinate slide-rod normally out of register therewith, and a key adapted to engage both when in register substantially as described.

4. In a voting-machine, the combination of a voting-slide, a slide-rod normally out of register therewith, and a key adapted to engage both when in register and move them concurrently, and independent means for moving the slide-rod to normal position.
5. In a voting-machine, the combination of a plurality of voting-slides, a slide-rod normally out of register, but adapted to coact therewith alternatively, and a key to engage the slides and the rod when in register.
6. In a voting-machine, the combination of a plurality of voting-slides, coördinate members adapted when in register with the slides to permit concurrent movement by a key, means for locking the slides, and a key adapted to unlock a slide and move it concurrently with the coördinate member, substantially as described.
7. In a voting-machine, the combination of a key-actuated voting-slide, a key-actuated coördinate slide-rod normally out of register with the slide, a key to engage both when in register, a lever to move the slide-rod to normal position, and a connection of said lever with the slide-rod.
8. In a voting-machine, the combination of a plurality of voting-slides, means for locking said slides against movement to voting position, a plurality of coördinate slide-rods adapted for key connection with the slides when in register, and normally out of register therewith, a key engaging both the slides and slide-rods when in register, and adapted to unlock the slide at its initial position, and means for moving the slide-rods to normal position independent of said key.
9. In a voting-machine, the combination with a series of vote-designating members corresponding to a party-ticket, an entrance-lever, and a connection thereof with said members adapted to move them positively to voting position before any vote-designating member can be moved separately, substantially as described.
10. In a voting-machine, the combination with a series of vote-designating members corresponding to a party-ticket, of an entrance-lever and a connection thereof with said series of members whereby they are moved positively to voting position, and a lock to prevent change in their position except singly and alternately.
11. In a voting-machine, the combination with locking mechanism normally out of register with vote-designating members, of a series of said members corresponding to a party-ticket, an entrance-lever, and mechanism connecting said lever with said series, whereby all are moved to voting position and in register with the locking mechanism by said entrance-lever.
12. In a voting-machine, the combination of multiple series of vote-designating members, mechanism adapted to lock all of said members except such as register therewith, and normally out of register with all of them, an entrance-lever, and mechanism connecting said lever alternatively with any one of said series and adapted to move it into register with the locking mechanism.
13. In a voting-machine, the combination of one or more series of voting-slides, mechanism adapted to lock them in normal position, a bail adapted to engage a series of slides and move them all into register with the locking mechanism, and an entrance-lever connected with said bail.
14. In a voting-machine, the combination of multiple series of voting-slides, locking mechanism therefor and normally out of register therewith, mechanism adapted to move a series of slides into register with the locking mechanism, and a key to engage the slides and the locking mechanism when in register, whereby the slides may be moved singly back and forth, substantially as described.
15. In a voting-machine, the combination of one or more vote-designating members, locking mechanism therefor, an entrance-lever connecting by suitable mechanism with said members and adapted to move them into register with the locking mechanism, and an exit-lever connecting with the locking mechanism, and adapted to move it out of register with said members.
16. In a voting-machine, the combination of multiple series of vote-designating members, a coördinate series of locking devices adapted, when in register, to coact therewith, a key adapted to engage both parts when in register, and a coupler for two or more of the locking devices, substantially as and for the purpose set forth.
17. In a voting-machine, the combination of voting-slides arranged in columns and rows, locking devices in rows corresponding to and coacting with the slides through the medium of a key, a mutually-engaging key, and a coupler to connect two or more of the locking devices.
18. In a voting-machine, the combination of multiple series of voting-slides normally locked out of voting position, locking mechanism normally out of register therewith, mechanism adapted to move any one series of slides into primary voting position and in register with the locking mechanism, and a key whereby the voter is enabled to move the slides and locking mechanism singly and alternately, and a coupler to connect two or more of the locking devices, substantially as and for the purpose set forth.
19. In a voting-machine, the combination with multiple series of voting-slides adapted for independent engagement with locking slide-rods, a series of reciprocating slide-rods adapted to engage singly with the slides, and a coupler to connect two or more of said rods, whereby the several candidates in any group

- may be voted for in any order singly but without duplication.
20. In a voting-machine, the combination with voting-slides corresponding to the various candidates, of a classifier comprising a series of reciprocating members corresponding to the various offices, means for connecting any desired number of them so as to move simultaneously, and a connection of each with a row of slides corresponding to an office.
21. In a voting-machine, the combination with voting-slides corresponding to the various candidates and offices, of a classifier comprising a series of reciprocating members with multiple points of engagement with actuating mechanism, a connection of each with a row of slides corresponding to an office, and a series of independently-moving bails, to engage said reciprocating members at diverse points, substantially as described.
22. In a voting-machine having movable vote-indicating members, a classifier comprising a series of movable members corresponding to the various offices; a connection thereof with their appropriate voting members, means for moving any number of selected classifier members, and means for restoring all to primary position.
23. In a voting-machine having voting-slides for the various candidates arranged as to tickets and offices, a classifier comprising a series of oscillating arms with removable studs at intervals thereon, a connection of said arms with slides of corresponding offices, a series of levers or bails adapted to engage such studs as lie in their paths, and means for bringing any one of said bails into action.
24. In a voting-machine, having vote-slides for the various candidates, and connections thereof by offices with the classifier, a classifier comprising a series of oscillating members, each connecting with the vote-slides of its appropriate office, means for bringing any desired set of said members into action, and an indicator to denote the set so selected.
25. In a voting-machine, a classifier comprising a series of oscillating arms or sectors corresponding to the various offices, removable studs therefor, bails adapted to engage the studs lying in their paths, a sliding rock-shaft adapted to separately engage said bails, and means for oscillating said shaft and for restoring all the parts to primary position.
26. In a voting-machine, the described classifier, comprising a rock-shaft provided with a sector-engaging stud, a sleeve on said shaft, a bail fixed to said sleeve, a series of sectors mounted loosely on said sleeve, and provided with removable studs to engage actuating-bails, and one or more bails mounted loosely on said sleeve and adapted to engage the rock-shaft studs.
27. In a voting-machine having members corresponding to the various candidates ar-

ranged as to tickets and offices, an entrance-lever and connected mechanism adapted to move one party-ticket slide to voting position, a classifier adapted to separate therefrom certain candidates' slides, and a connection of the entrance-lever with the classifier whereby the secondary action of said lever throws out of action all slides not properly included in the particular class.

28. The combination in a voting-machine having voting-slides, substantially as shown, of a classifier adapted to throw certain voting-slides out of action, an entrance-lever and connected mechanism adapted to operate the canceling portion of said classifier, an exit-lever and connected mechanism to restore the whole classifier to primary position.

29. In a voting-machine having vote-designating slides for the regular candidates and covering-slides for independent candidates, a series of lock bars or rods independent of said slides and normally out of register therewith, a key adapted to actuate the slides and lock-bars when in register, a movable web for independent ballots normally covered by the independent-ticket slides, an exit-lever, mechanism adapted to restore the slides and lock-bars to initial position and advance the web, and a connection of the exit-lever with said restoring mechanism.

30. In a voting-machine having vote-designating members arranged as to tickets and offices, the combination of an entrance-lever, a ticket-selecting indicator adapted to bring the entrance-lever into actuating relation with the ticket-slides so indicated, and a connection of said lever with such selecting mechanism, whereby, through the joint action of the indicator and the entrance-lever the voter arranges a straight ballot as the first act in voting.

31. In a voting-machine having vote-designating members arranged as to tickets and offices, and mechanism adapted to move to voting position all of any set corresponding to a party-ticket, the combination of a lever connected with said mechanism, and a ticket-selecting indicator adapted to release the lever as to the ticket selected, and permit the voting of said party-ticket as a whole.

32. In a voting-machine having voting-slides an actuating-lever to move them to voting position, and connecting mechanism, substantially as described, a party-ticket-selecting indicator which sets the connecting mechanism and locks the machine, except as set for some party-ticket.

33. In a voting-machine having voting-slides arranged as to party-tickets and offices, bails adapted to move to voting position an entire set of party-ticket slides, a ticket-selector adapted to register with a single selected ticket-bail, and a lever connecting with said ticket-selector, substantially as described.

34. In a voting-machine having entrance

and exit levers, voting-slides and connecting mechanism, a party-ticket-selecting device, and means adapted to normally lock the entrance-lever and to release the same only when the selecting device is set to any party-ticket, 5 and a connection of said selecting device with the exit-lever whereby it is restored to normal position in the final act of voting.

35. A party-ticket-selecting device for a voting-machine, comprising a rotatable and sliding sleeve, an indicator adapted to turn the same, a lever and connection to slide said sleeve, studs projecting from the sleeve radially in different planes, and levers corresponding to the 10 various party-tickets to engage said studs successively when brought into register with the indicator and moved by said lever.

36. In a voting-machine, the combination of a voting-slide, a pawl with an extended nose, 15 connecting therewith, adapted to be lifted by a key, a counter with which said pawl engages in the final act of voting, and a carrier to engage said pawl-nose and support the pawl free from the counter until said final act.

25 37. In a voting-machine, the combination of a voting-slide, a key-actuated pawl with an extended nose, connected therewith, a carrier for said pawl-nose during the preliminary operations of voting, a counter with which the 30 pawl finally engages, and a key to tilt the pawl while moving the slide back and forth.

38. In a voting-machine, the combination of a voting-slide, a key-lifted pawl with an 35 extended nose, attached thereto, a carrier adapted to support the pawl-nose when moved to voting position and to lock other pawls not

in the same position, and a counter with which the pawl finally engages.

39. In a voting-machine, the combination of a voting-slide, a key-lifted pawl attached thereto, a counter with which the pawl finally engages, a carrier adapted to hold the pawl away from the counter, entrance and exit levers, a connection of the entrance-lever with the carrier whereby it is moved to supporting position, and a connection of the exit-lever with the slide and carrier, whereby the latter is restored to primary position and the pawl is left unsupported. 45

40. In a voting-machine, a plurality of vote-arranging members for a multiple-candidate office, locking mechanism therefor adapted to act as a unit, and means whereby said vote-arranging members move the locking mechanism back and forth in arranging the ballot. 50

41. In a voting-machine, a plurality of vote-designating members corresponding to party-tickets and offices, locking mechanism therefor adapted to act as a unit in each office, and mechanism adapted to positively move to 55 voted position a set of vote-designating members corresponding to a party-ticket as the initial act in voting, and before the locking mechanism can be moved back and forth in arranging the ballot. 60

In testimony whereof I affix my signature in presence of two witnesses.

WILLIAM GLENN.
